2,677,845

NOZZLE ADJUSTMENT FOR SUCTION
CLEANERSGeorge P. Daiger, Canton, Ohio, assignor to The
Hoover Company, North Canton, Ohio, a cor-
poration of Ohio

Application October 25, 1949, Serial No. 123,516

6 Claims. (Cl. 15—333)

1

This invention relates to suction cleaners and more particularly to improvements in nozzle height positioning means in a suction cleaner.

Suction cleaners are usually provided with a nozzle height adjusting device which is manually adjusted. A disadvantage of this type of manual nozzle adjustment is that the operator unknowingly mis-sets the device by adjusting the nozzle to a higher position than required and thereafter continues to use the cleaner with the nozzle improperly adjusted. In the suction cleaner constructed according to the present invention a normal nozzle height position is provided for optimum cleaning efficiency for a relatively wide range of rugs, and a manual device is provided for moving the nozzle to a higher adjusted position for extremely thick rugs. The manual device is rendered inoperative when the cleaner handle is moved to a rest or storage position and the nozzle is automatically preset to return to its normal position upon movement of the handle into its operating range. Thus the operator can not continue to use the cleaner with the nozzle adjusted to a higher position than is required.

It is an object of the invention to provide a novel and improved suction cleaner. Another object is to provide a nozzle height adjusting device in a suction cleaner. A further object is to provide a suction cleaner having a normal nozzle position for all but extremely thick rugs, an adjusted nozzle position for extremely thick surface coverings and means to automatically readjust the nozzle to its normal nozzle position. Another object is to provide a suction cleaner wherein the nozzle is automatically returned from its high adjusted position to its lower normal operating position upon movement of the cleaner handle from its rest position. Other objects and advantages of the invention will be apparent from the following description and drawings, wherein:

Figure 1 is a bottom view of the cleaner with parts broken away;

Figure 2 is a view taken along the line 2—2 of Figure 1 and showing the nozzle in its normal position;

Figure 3 is a view similar to Figure 2 but showing the nozzle adjusting means in its high position to adjust the nozzle for extremely thick rugs, and also shows in dotted lines the handle in a rest position to raise the nozzle a greater distance from the rug; and

Figure 4 is a perspective view of the nozzle adjusting device.

The embodiment of the invention herein dis-

2

closed comprises a cleaner body provided with a nozzle 10, from which extends an air passage-way 11 and a belt conduit 12 each terminating in a trunnion 13 on which is rotatably mounted 5 a motor fan unit 14 having a fan chamber 15 provided with an inlet 16. Disposed in the fan chamber 15 is a suction creating fan 17 driven by an unshown motor having its shaft provided at its opposite end with a belt pulley 18 projecting into the belt conduit 12. A belt 19 extends from the pulley 18 through the conduit 12 to a surface agitator 20 rotatably mounted in the nozzle 10. An opening 21 is provided in the suction air passageway 11 opposite the fan chamber inlet 16 for reception of an unshown converter when it is desired to employ the cleaner for off-the-floor cleaning. A cover 22 normally closes the port 21. Extending from the fan chamber 15 is an outlet 23 to which the lower end of a dirt filtering bag 24 is connected and the latter is attached at its upper end to a handle 25 supported on the housing of the motor fan unit 14.

The combined handle 25 and motor fan unit 14 are yieldably held in the low position shown 25 in Figure 2 and in rest position shown in dotted lines in Figure 3 by a spring-pressed lever 27 rotatably mounted on the stationary portion of the cleaner body and provided with a roller 28 which rides upon an arcuate sector 29 formed on the motor-fan housing, and the sector 29 is provided with seats 30 and 31. When the handle 25 is in its lower position the roller 28 is in the seat 30 and when in storage position the roller engages the seat 31 to retain the handle in these positions unless an external force is exerted thereon.

The cleaner body is supported on front wheels 33—33 and rear wheels 34—34 the latter being mounted on brackets 35 extending from the cleaner body. The treads of the front wheels 33 are relatively broad in comparison to the rear wheels 34 and this combination of wheel treads provides automatic adjustment of the nozzle 10 for a wide range of rugs. The front wheels 33 are rotatably mounted on the offset ends 36 and 37 of a shaft 38 having other offset portions 39—39 which are rotatably attached to the cleaner body by brackets 40 and 41.

The mid-portion 43 of the shaft 38 is angularly offset downwardly with respect to the shaft portions 39, and a spring 44 forming part of the bracket 40 bears against the shaft portion 43 to rotate the shaft clockwise, as viewed in Figure 2, about its pivotal axis 39 and thus move the front 55 wheels 33 toward normal nozzle position.

Cooperating with the wheel shaft 38 is a foot operated nozzle adjusting device comprising a lever 45 pivotally mounted on a pin 46 supported by a lug 47 and the side wall 48 of the cleaner body, and the lever projects through a slot 49 in the body and is provided at its outer end with a pad 50 to receive the operator's foot. A torsion spring 51 normally urges the lever 45 clockwise, as viewed in Figure 2, against the upper stop limit 52 of the slot 49.

An elongated slot 53 is provided at the inner end of the lever 45 and rotatably receives a pin 54 mounted at one end on a sector 55 pivotally supported on a pin 56 attached to the body side wall 48. Two seats 57 and 58 are formed in the sector 55 for engagement with the offset portion 37 of the wheel shaft 38, and when the latter is in the seat 57 the nozzle is adjusted in its normal position relative to the rug indicated at 60, as shown in Figure 2, and when the seat 58 receives the shaft end 37 the wheels 33-33 are moved downwardly to raise the nozzle to its adjusted position relative to the rug 61, shown in Figure 3, for cleaning extremely thick rugs.

In order to raise the nozzle 10 and the agitator 20 to an inoperative position relative to the supporting surface a member 65 is rigidly attached to the offset portion 39 of the wheel shaft 38 and extends into the path of a pin 66 mounted on the housing of the rotatable motor fan unit 14. When the handle 25 is rotated through its normal operating range the pin 66 does not contact the member 65, but upon moving the handle 25 to its rest or storage position shown in dotted lines in Figure 3, the pin 66 engages the member 65 to rotate the wheel shaft counterclockwise and lower the front wheels 33 to thereby raise the nozzle 10 and agitator 20 to an inoperative position with reference to the rug indicated at 67.

In the operation of the cleaner on all but extremely thick rugs the manual nozzle adjusting device is in its normal position shown in Figure 2 with the lever 45 urged by the spring 51 against the top 52 of the slot 49 and the sector seat 57 resting against the offset portion 37 of the wheel shaft, to thereby maintain the front wheels 33 and the nozzle 10 in their normal positions. The shaft spring 44 exerts a force on the lowest offset portion 43 of the wheel shaft 38 to rotate the latter clockwise as viewed in Figure 2 to urge the wheel shaft offset 37 into the sector seat 57. In this normal position of the nozzle 10 the broad and narrow wheels 33 and 34 respectively maintain the nozzle 10 at an optimum nozzle height for rugs of different pile depth except for extremely thick rugs.

The sector seat 57 maintains the front wheels 33 in their normal nozzle position during movement of the handle 25 throughout its normal operating range while moving the nozzle 10 over the rug being cleaned. If the handle 25 is moved to its storage position the pin 66 on the motor fan unit housing engages the member 65 causing the wheel shaft 38 to rotate counterclockwise, as viewed in Figure 2, about its pivotal axis 39 and disengages the wheel shaft offset 37 from the sector seat 57 to lower the front wheel 33 and raise the nozzle 10 and also the agitator 20 out of operating engagement with the rug. In this inoperative position of the nozzle 10 the cover plate 22 can be removed and a converter inserted through the port 21 for connection with the fan eye 16 to convert the cleaner for off-the-floor cleaning. While the handle 25 is in storage lever 45.

position the sector seat 57 is retained in its normal nozzle position by the spring 51 maintaining the lever 45 in the same position against the top 52 of the slot 49 so that the sector seat 57 is positioned to receive the wheel shaft offset 37. Upon movement of the handle 25 from its storage position into its operating range the pin 66 moves out of engagement with the member 65 to permit the shaft spring 44 to rotate the wheel shaft clockwise, as viewed in Figure 2, and move the shaft offset 37 into engagement with the sector seat 57 and thus reset the nozzle 10 to its normal nozzle position.

If it is desired to clean an extremely thick rug the operator places his foot on the pad 50 depressing the lever 45 against the force of the spring 51 and rotating the sector 55 clockwise to the position shown in Figure 3, whereby the sector seat 58 receives the wheel shaft offset 37 and rotates the shaft 38 counterclockwise about its axis 39 to thereby lower the front wheels 33 and raise the nozzle 10 to its adjusted nozzle position with reference to the extremely thick rug 61. In this position of the sector 55 the spring 51 urges the sector seat 58 against the shaft offset 37 to retain the latter in adjusted position, and the shaft spring 44 exerts a force against the lowest wheel shaft offset 43 to assist in seating the shaft offset 37 in the sector seat 58.

Referring to Figure 3, upon movement of the handle 25 from its operating range to its storage position the pin 66 engages the member 65 which rotates the wheel shaft offset 37 counterclockwise to lower the front wheels 33 to their dotted line position and thus the nozzle 10 and agitator 20 are raised and held out of operating engagement with the rug 67. The spring-pressed roller 28 engages the seat 31 to hold the motor fan unit and handle in storage position. Upon movement of the handle 25 to its storage position, the wheel shaft portion 37 moves out of the sector seat 58 to its dotted line position, and thereafter the sector 55 is automatically rotated counterclockwise by the torsion spring 51 to reset the sector seat 57 in position to receive the wheel shaft portion 37 for rearranging the nozzle to its normal position when the handle 25 is moved into its operating range. The sector 55 is controlled in its movement to its reset normal nozzle position by the lever 45 abutting the stop 52 at the top of the slot 49. Upon movement of the handle 25 from storage position into its operating range the pin 66 is disengaged from the member 65 and the shaft spring 44 exerts a force on the lowest offset shaft portion 43 to rotate the shaft clockwise and raise the front wheels until the wheel shaft portion 37 is received in the sector seat 57 to again reset the nozzle 10 to its normal position.

From the foregoing it will be perceived that when the lever 45 is depressed to move the sector seat 58 into engagement with the wheel shaft portion 37 the nozzle 10 is raised to its adjusted position for cleaning extremely thick rugs. Thereafter if the handle is moved to storage position the sector 55 is automatically shifted to be in position to receive the wheel shaft portion 37 and thus reset the nozzle to its normal nozzle position upon movement of the handle into its operating range. The operator thus lowers the nozzle 10 from a previously set high position upon moving the handle into and out of storage position, and prevents continued use of the nozzle in high adjusted position. If the high nozzle position is required the operator depresses the lever 45.

While I have shown and described but a single modification of my invention, it is to be understood that this modification is to be taken as illustrative only and not in a limiting sense. I do not wish to be limited to the particular structures shown and described, but to include all equivalent variations thereof except as limited by the scope of the claims.

I claim:

1. In a suction cleaner, a body, a nozzle on said body, nozzle adjusting means including normal nozzle positioning means and adjusted nozzle positioning means to move said nozzle to normal and adjusted positions with respect to the floor covering being cleaned, first means on said body for moving said nozzle to an inoperative nozzle position with respect to the floor covering, latching means on said body for maintaining said nozzle in said inoperative position, said first means disconnecting said adjusted nozzle positioning means when said nozzle is in said inoperative position, and means shifting said normal nozzle positioning means into operative position for readjusting said nozzle to said normal nozzle position when said nozzle is moved from its inoperative position.
2. In a suction cleaner, a body, a nozzle on said body, nozzle adjusting means including means supporting said nozzle with respect to the floor covering being cleaned and normal nozzle positioning means and adjusted nozzle positioning means for relative adjustment of said body and said supporting means to move said nozzle to normal and adjusted positions with respect to the floor covering, first means on said body for raising said nozzle to an inoperative position with respect to the floor covering, said first means disconnecting said adjusted nozzle positioning means with respect to said supporting means, and means operable upon movement of said nozzle to its inoperative position to shift said normal nozzle positioning means into operative position with respect to said supporting means for readjusting said nozzle to said normal nozzle position when said nozzle is moved from its inoperative position.
3. In a suction cleaner, a body, a nozzle on said body, nozzle adjusting means including normal nozzle positioning means and adjusted nozzle positioning means to move said nozzle to normal and adjusted positions with respect to the floor covering being cleaned, a handle mounted on said body and movable to and from a position of rest, means actuated by said handle for raising said nozzle to an inoperative position with respect to the floor covering when said handle is moved to its said rest position, said means operatively connected with said nozzle adjusting means to disconnect the latter when said handle is in its rest position, and means operable when said handle is moved to its said rest position to render said adjusted nozzle positioning means inoperative and said normal nozzle positioning means operative for normal nozzle position upon movement of said handle from its said rest position.

4. In a suction cleaner, a body, a nozzle on said body, nozzle adjusting means including means supporting said nozzle with respect to the floor covering being cleaned and normal nozzle positioning means and adjusted nozzle positioning means for relative adjustment of said body and said supporting means to move said nozzle to

normal and adjusted nozzle positions with respect to the floor covering, a handle mounted on said body and movable to and from a rest position, means actuated by said handle for moving said supporting means to raise said nozzle to an inoperative position with respect to the floor covering when said handle is in its said rest position, said means disconnecting said nozzle adjusting means when said handle is in said rest position, and means operable when said handle is in its said rest position to render said adjusted nozzle positioning means inoperative and said normal nozzle positioning means operative with said supporting means for normal nozzle position upon movement of said handle from its rest position.

5. In a suction cleaner, a body, a nozzle on said body, wheel supporting means on said body for supporting said nozzle with respect to the floor covering to be cleaned, nozzle control means including normal nozzle positioning means and adjusted nozzle positioning means cooperating with said wheel supporting means to adjust said nozzle to its normal and adjusted positions with respect to the floor covering, means for moving said nozzle control means to its normal and adjusted nozzle positions, a handle on said body and movable to and from a position of rest, means actuated by said handle to render said nozzle control means in operative with respect to said wheel supporting means when said handle is moved to said rest position, and means automatically operable upon movement of said handle to said rest position to shift said normal nozzle positioning means into position to cooperate with said wheel supporting means upon movement of said handle from its rest position to shift said nozzle to its normal position.
6. In a suction cleaner, a body, suction creating means in said body, a nozzle connected with the fan chamber of said suction creating means, nozzle supporting means, means for converting said suction creating means for dusting tool operation including a port leading to said fan chamber and adapted to receive a converter member, normal nozzle positioning means and adjusted nozzle positioning means to move said nozzle to normal and adjusted positions with respect to the floor covering being cleaned, means on said body connectible with said nozzle supporting means for moving said nozzle to and from converter operating position to receive the converter member when in converter operating position, said means disconnecting said adjusted nozzle positioning means when said nozzle is in converter operating position, and means automatically operable upon movement of said nozzle to its said converter operating position to render said disconnected adjusted nozzle positioning means inoperative and shift said normal nozzle positioning means into operative position for readjusting said nozzle to said normal position when said nozzle is moved from its converter operating position.
